UNITED STATES PATENT OFFICE.

MATTIE M. BURKE, OF LOS ANGELES, CALIFORNIA.

DESIGN FOR AN APRON.

58,993.

Specification for Design. Patented Sept. 13, 1921.

Application filed May 26, 1921. Serial No. 472,904. Term of patent 3½ years.

To all whom it may concern:

Be it known that I, MATTIE M. BURKE, a citizen of the United States, residing at Los Angeles, in the county of Los Angeles and State of California, have invented a new, original, and ornamental Design for Aprons, of which the following is a specification, reference being had to the accompanying drawing, forming a part thereof, in which—

Fig. 2 is a rear elevation of the same.

I claim:

The ornamental design for an apron as shown.

MATTIE M. BURKE.
